[57] ABSTRACT

A motor is mounted in an upper floor adjacent an opening between the upper floor and an adjacent lower floor of a structure. A coupling device is provided in a stair unit and the motor so that in one manner of operation the motor retracts the stair unit upward onto the upper floor through the opening and closes the stair unit substantially flush with the upper floor. In another manner of operation, the motor opens the stair unit downward from the upper floor and extends the stair unit downward onto the lower floor through the opening.

FIG. I

FIG. 2

RETRACTABLE STAIRWAY DEVICE

DESCRIPTION OF THE INVENTION

The present invention relates to a retractable stairway device.

The principal object of the invention is to provide a retractable stairway device of simple structure, which is inexpensive in manufacture and functions with efficiency, effectiveness, reliability and rapidity to retract and extend a stairway between adjacent floors of a structure.

In order that the invention may be readily carried into effect, it will now be described with reference to the accompanying drawing, wherein:

FIG. 1 is a side view of the retractable stairway device of the invention in open position; and

FIG. 2 is an end view of the retractable stairway device of the invention in closed position.

In the FIGS., the same components are identified by the same reference numerals.

The retractable stairway device of the invention is provided in an opening 1 between an upper floor 2 and an adjacent lower floor 3 of a structure (FIG. 1). The stairway device of the invention selectively provides access between the floors 2 and 3.

The retractable stairway unit of the invention comprises a stair unit 4 (FIGS. 1 and 2). A reversible motor 5 (FIGS. 1 and 2) is mounted on the upper floor 2 adjacent the opening 1 between the floors and may comprise any suitable motor such as, for example, an electric motor, a hydraulic motor, an electrohydraulic motor, or the like.

A trap door panel 6 (FIGS. 1 and 2) is mounted in the opening 1 between the floors and is coupled to the motor 5 by a coupling device 7 of any suitable type for pivotal movement by the motor from a position flush with the upper floor and closing the opening, as shown in FIG. 2, to a position extending at an angle between the floors, as shown in FIG. 1.

The trap door panel 6 has a pair of spaced substantially parallel tracks 8 and 9 mounted therein (FIG. 2). The stair unit 4 is slidably mounted on the tracks 8 and 9.

A coupling device such as, for example, a rack and pinion arrangement 10 (FIG. 2) is provided on the stair unit 4 and the motor 5. Thus, when the motor 5 is operated in one direction of rotation, said motor moves the stair unit 4 via the rack and pinion 10 in an upward direction, indicated by an arrow 11 (FIG. 1), along the tracks 8 and 9 of the trap door panel 6 until the bottom

12 of said stair unit clears the free edge 13 (FIG. 1) of the trap door panel.

The trap door panel 6 is then pivotally moved by the motor 5 via the coupling 7 to a position flush with the upper floor 2 in which it closes the opening 1 (FIG. 2).

When the motor 5 is operated in the opposite direction of rotation, said motor opens the trap door panel 6 via the coupling 7 to a position extending at an angle between the floors. The motor then moves the stair unit 4 via the rack and pinion 10 in a downward direction along the tracks 8 and 9 of the trap door panel 6 until the bottom 12 of said stair unit is substantially adjacent the lower floor 3, as shown in FIG. 1.

The motor 5 is preferably coupled to the trap door panel via a gear coupling 7, whereby said motor pivotally moves said trap door panel in a desired direction. The motor 5 moves the stair unit 4 in a desired direction via the rack and pinion 10.

I claim:

1. A retractable stairway device in an opening between an upper floor and an adjacent lower floor of a structure for selectively providing access between the floors, said retractable stairway device comprising a stair unit;

motor means on the upper floor adjacent the opening between the floors;

a trap door panel mounted in the opening and coupled to the motor for pivotal movement by the motor from a position flush with the upper floor and closing the opening to a position extending at an angle between the floors, the stair unit being slidably mounted on the trap door panel; and rack and pinion means coupling the stair unit to the motor means in a manner whereby in one manner of operation the motor means moves the stair unit in an upward direction along the trap door panel until the bottom of the stair unit clears the free edge of the trap door panel and in another manner of operation the motor means moves the stair unit in a downward direction along the trap door panel until the bottom of the stair unit is substantially adjacent the lower floor.

2. A retractable stairway device as claimed in claim 1, wherein the motor means is a reversible motor.

3. A retractable stairway device as claimed in claim 1, wherein the trap door panel has a pair of spaced substantially parallel tracks mounted thereon and the stair unit is slidably mounted on the tracks.
